TEMPERATURE CONTROL DEVICE

Hallan Eugene Goldstine, Rocky Point, N. Y., assignor to Radio Corporation of America, a corporation of Delaware

Application October 30, 1936, Serial No. 108,434

3 Claims. (Cl. 236—1)

This invention relates to a new and novel piezo-electric crystal oven and holder.

An object of this invention is to improve the temperature regulation within a crystal oven of a piezo-electric crystal.

Another object of this crystal unit is to keep the oven wall temperature the same on all sides of the crystal box and thus prevent large differences in temperature within the crystal unit.

10 Still another object of this invention is to provide a temperature regulator for a piezo-electric crystal holder in which the holder is arranged with cooling members to maintain constant temperature on the crystal.

15 A feature of this invention is the arrangement of the cooling members within the oven so as to smooth out the variations in the temperature.

Another feature of this invention is the arrangement of cooling members located on the 20 electrode of the crystal holder to smooth out variations in temperature.

25 Although piezo-electric crystal holders and ovens for maintaining the wall at constant temperature are old in the art, I have found that in the construction of the crystal oven it is necessary to either keep the crystal holder itself at a predetermined temperature by insulating it from the ambient temperature so that changes in the ambient temperature would have little 30 effect on the change of the crystal holder, or to hold the temperature of the oven wall at a constant temperature by supplying a thermostatic element for controlling the temperature, which element may be in the form of a bimetallic strip.

35 When a bimetallic strip type of thermostat is used, it is found desirable to distribute the heat more evenly within the oven, so that the temperature within the oven will be uniform. However, when using such a bimetallic strip type 40 of thermostat, it is generally difficult to get good thermal conductivity between the thermostat and the wall. By this invention, the temperature near thermostat element is maintained substantially constant by placing it within a thin 45 metallic tube which is connected to the wall of the container for the piezo-electric crystal. Also, when desired, the crystal holder itself is arranged with a number of metallic fins for radiating the heat developed within the crystal.

50 The crystal holder is so constructed that the heat developed by the crystal may be dissipated to the air in the box by means of copper radiating fins, and also the crystal if placed in the box cold will reach the box temperature faster than 55 normal due to the better heat conductivity from

the box air temperature to the crystal. This will reduce the frequency change due to the crystal heating when oscillating, because the crystal will not get as hot and it will not take as long to reach an equilibrium with the box temperature. 5

The crystal container may also have enclosed part of the apparatus of the crystal circuit, such as a coil and condenser whereby they are also held at a fixed temperature.

This invention will be more completely understood by referring to the accompanying drawing, in which:

Fig. 1 is a front view partly in section through the crystal oven;

Fig. 2 is a side view partly in section taken on 15 lines A—A of Fig. 1;

Fig. 3 is a plan view of the crystal holder; while

Fig. 4 is a section of Fig. 3.

Referring now in detail to the drawing, the 20 oven 1 is composed of a fiber box 2 having an insulating space 3 which is filled with any suitable insulation material, such as felt. The felt is covered with a mica sheet 4 on which is located the heating element or winding 5. Outside of the 25 winding there is a mica sheet between the heater and wall or shield 6, preferably made of heavy copper. A thermostat 7, which may be of the type having a bimetallic strip or thermostat, is supported within a metallic tubular container 8, 30 preferably of copper. One end of container 8 is provided with an insulating bushing 9 which is composed preferably of a phenol condensation product, to electrically insulate one side of the thermostat from shield 6. However, if the 35 thermostat is to be operated so that there is no potential difference between it and the metallic tubular sleeve 8, there would be no need of using the insulating bushing 9. The outer portion of tube 8 has located thereon a plurality of metallic 40 fins or heat conducting members 10 which are equally spaced. The purpose of fins 10 is to provide a plurality of heat conducting vanes to maintain metallic tube 8 at substantially the same temperature as the inner walls 6 of box 2 so that 45 the thermostat 7 responds more promptly to the wall temperature than if a solid metallic member were used, for the reason that a solid member would tend to be sluggish in operation and thus retain the heat. The thermostat housing is 50 supported on the copper shield 6 by means of a metallic plate 11 which is secured by any suitable means, such as, for example, by soldering to the metallic fins 10. The heating element 5 comprises a plurality of heater wires located on 55

five sides of the box, all except the front. They may be located in the front also, if connections are provided to disconnect the heater when the front is removed. The heater is then electrically insulated from the copper wall of the crystal box by means of a thin sheet of mica. This gives good thermal contact from the heater to the copper wall.

5 A piezo-electric crystal holder is shown in Figs. 10 3 and 4 and consists of an upper electrode 12 and a lower electrode 13, the electrodes being placed apart from each other by a metallic ring 14 and an insulating member 15. A connection is taken from the upper electrode 12 by a terminal member 16 and from the lower electrode 13 by a terminal member 17, the crystal 18 being located substantially central within the space between electrodes 12 and 13. The lower electrode 13 is 15 provided with a plurality of radiating fins 19, which are preferably composed of any good heat conducting material, such as copper.

18 The piezo-electric crystal holder is located within the container by two insulating supports 21 firmly secured to the copper shield 6. 25 Knurled nuts 22 are provided to clamp the piezo-electric crystal holder to the insulating supports 21.

30 While only one modification of this invention is shown, it is distinctly understood that this invention is not to be limited to the one shown, but is capable of taking other forms, and therefore should not be limited to the form shown, except as to such limitations as are clearly imposed in the appended claims.

35 What is claimed is:

1. A temperature control device comprising a 40 casing having inner walls of high thermal conductivity metal, a heating element within the walls of said casing, a thermostat to control said heating element to maintain the temperature of

said walls substantially the same, means to make said thermostat immediately respond to changes in temperature within said casing, said means comprising a hollow metallic member surrounding said thermostat and located parallel to one of the walls of said casing and closely adjacent thereto, and a plurality of heat conducting vanes mounted outside of said metallic member and secured to the wall by a metallic plate.

2. A temperature control device comprising a 10 casing having inner walls of high thermal conductivity metal, a heating element within the walls of said casing, a thermostat to control said heating element to maintain the temperature of said walls substantially the same, means to make 15 said thermostat immediately respond to changes in temperature within said casing, said means comprising a tubular metallic member located parallel to and closely adjacent to one of the walls of said casing, said tubular member enclosing said thermostat, and a plurality of heat conducting vanes mounted outside of said metallic member and in a plane at right angles to said wall and connected thereto.

20 3. A temperature control device comprising a 25 casing having inner walls of high thermal conductivity metal, a heating element within at least five walls of said casing, a thermostat to control said heating element to maintain the temperature of said walls substantially the same, means to make 30 said thermostat immediately respond to changes in temperature within said casing, said means comprising a tubular metallic member located parallel to and closely adjacent to one of the walls of said casing, said tubular member enclosing said thermostat, and a plurality of heat conducting vanes mounted outside of said metallic member and in a plane at right angles to said wall and connected thereto.
